UNITED STATES PATENT OFFICE.

EDWIN L. WIEGAND, OF DORMONT, PENNSYLVANIA.

ELECTRIC STRIP HEATER.

Application filed July 31, 1925. Serial No. 47,224.

This invention relates generally to the class of electrical heating units known as "strip" or "space" heaters, and more especially to one that is peculiarly suited for use in broilers of the kind employed in hotels and restaurants where electrical appliances of this character are required to operate at very high temperatures for many hours running. The invention has to do also with a combination of my improved strip heater with a heat returning element or reflector of suitable design. In the more complete embodiment of this combination, the heat returning element has a novel contour or shape that is related in a very definite way to the arrangement of the heating units.

While I have stressed the importance of the invention with respect to broilers, it will be understood that it is of general application, another instance of its use being in connection with a reflector type electric room heater.

Where I use the term "reflector" in connection with broiler equipment, it is used in its broadest sense, and in some instances may be a heat returning element or baffle constructed of fire clay or other suitable refractory material, minus the usual brilliant surface suggested by the ordinary use of the word "reflector".

More generally the invention may be defined as consisting of the combination and arrangement of parts set out in the claims annexed hereto, and the principal objects sought to be attained may be enumerated as follows:

The provision of a heavy duty electric heater of the strip type that is so designed as to facilitate manufacture and impart rigidity to the strips, no intermediate or central support being required in the installation of the device;

To provide a strip heater of the foregoing nature in which radiation is effected at the most advantageous angles;

To provide a strip heater of very high efficiency, the nature of its construction and its shape being, in part, responsible for this, and, in part, the use of such material as nickel chromium alloy or other high temperature metal for the sheath that surrounds the embedded resistor; and

To combine with a strip heater of the character above set forth, a heat returning element which coacts with the heater in a unique way to conserve and reflect that portion of

the heat radiated from the strip which would otherwise be wasted thereby greatly enhancing the efficiency of the device.

The foregoing objects, with others herein-after appearing, are attained in the embodiments of the invention illustrated in the accompanying drawing wherein Fig. 1 is a perspective view of my improved strip heater; Fig. 2 is a fragmentary plan view showing one end of the strip applied to a support; Fig. 3 is a fragmentary longitudinal section on the line 3—3 of Fig. 2; Fig. 4 is a transverse section through the strip on the line 4—4 of Fig. 3; Fig. 5 is a sectional view through a broiler assembly incorporating, with my improved strips, a reflector or baffle; and Fig. 6 is a diagrammatic representation of an electric heater of the reflector type embodying the invention.

The strip heater, which is designated generally by the reference character 1, comprises an elongated sheath of suitable light sheet metal, preferably nickel chromium alloy because of its being a high temperature metal, and the same encloses a highly compacted mass of refractory, electrical insulating, heat conducting material, such as magnesium or aluminum oxid or zirconium silicate, preferably magnesium oxid, in which is embedded a suitable resistor. Excepting adjacent its ends, the strip has the cross-sectional shape shown in Fig. 4, the underneath or active face 1^a of the heater preferably defining a parabolic curve, while the back 1^b is only slightly convex.

In building the device, the edge portions of a trough-shaped casing 2, which constitutes the major part of the sheath, are left standing more or less upright until the mass of refractory, electrical insulating, heat conducting material 3 is placed therein. A resistor 5 is embedded within the mass or body of material 3, and the same is desirably, but not necessarily, composed of a suitable metallic ribbon or flat wire that is given a sinuous formation so as to distribute the resistor effectively throughout the strip.

After the body or mass of refractory insulating material 3, with the resistor 5 embedded therein, has been highly compressed within the casing 2, a cover 6, in the form of a metal strip, is placed on top of the material and the edges of the casing are turned over it to secure it in place. Before the edges of the casing are turned over, however, plates

7 of somewhat heavier material than the cover 6 are laid in the ends of the casing, and these plates are formed with openings 8 for the accommodation of binding posts 9 that are applied to the ends of the resistor 5. The openings 8 are ample to provide liberal spaces about the binding posts 9 and washers 11 of insulating material surround the binding posts and serve to insulate the terminals from the sheath. The extreme ends of the structure are flattened to provide attaching ears 12 having enlarged openings 13 through which screws 15 pass for binding the strip to a suitable support. In the present instance, a support 16 is shown as constituted of an angle bar, and the screw 15 passes through a hole in one flange of the bar and has a nut 17 applied to it beneath said flange, washers 18 being applied to the screw above and below the ear 12. The size of the opening 13 with respect to the screw 15 is such as will afford movement of the ends of the strip with respect to the screws to allow for expansion and contraction of the strip.

25 The arrangement of the strip heaters in broiling apparatus is shown in Fig. 5, the active faces 1^a being presented to a suitable grid 20 on which food to be broiled or toasted may be supported, and a suitable heat obstructing element or reflector 22 is situated above the heaters in spaced relation to their backs 1^b. The light line arrows appearing in said view indicate the radiation of heat from the strip heaters, while the heavy line arrows represent the heat that is radiated by the heat obstructing element or reflector 22, which, in the present instance, is preferably composed of suitable refractory material, such as fire brick, and its surface adjacent the strip heaters is corrugated to provide ribs 23 that are disposed directly above the backs of the strips. Heat is pocketed within the grooves between the ribs 23 and this heat, with that absorbed by the reflector, serves as a secondary radiator to intensify the primary radiation in the vertical zones between the strips. It will be seen from this that the design of the strip heaters 1 and the relation thereto of the heat obstructing element 22 contribute to the attainment of a very even distribution of the heat delivered to an object sustained by the grid 20. For instance, immediately below the heaters 1, the heat is thrown directly downwardly from the active faces of the heaters, while that which is thrown generally laterally therefrom has a greater distance to travel and accordingly is relatively less effective. However, throughout this area of less effective direct radiation, the heat that is radiated upwardly by the backs of the strips is reflected downwardly by the heat obstructing element 22 to augment the direct radiation thereby to equalize, so to speak, the heat throughout the area of the grid.

65 By the use of well known circuit arrange-

ments, at the option of the operator all of the strip heaters, or groups thereof less in number than that constituting the entire series, may be energized.

The embodiment of my improved strip in a room heater of the reflector type is illustrated in Fig. 6, the strip heaters 1 being disposed transversely of the structure immediately in front of a reflector 25, the active faces of the strips radiating heat directly into the room while the heat radiated from the backs of the strips is returned to the room by the reflector 25.

The construction and cross-sectional shape of my improved strip heater make it very stiff and rigid and not liable to becoming warped or distorted by the intense heat under which it is required to operate for many hours at a time. This obviates the use of undesirable central or intermediate supports which so frequently have to be resorted to in the use of tubular or strip heaters of prevailing kinds.

Having thus described my invention, what I claim is:

1. As a new article of manufacture, an electric strip heater comprising a resistor, a highly compacted mass of refractory, electrical insulating, heat conducting material enveloping said resistor, and a thin metal sheath completely enclosing the refractory material, the ends of said element being formed to provide attaching parts while the portion intermediate said ends is slightly convexed along one side while along the other side it has a pronounced transverse parabolic curvature so as to increase the radiating surface of said side and more widely diffuse the heat therefrom.

2. An electric strip heater comprising a resistor, a compacted mass of refractory, electrical insulating, heat conducting material enveloping said resistor, a thin metal sheath completely enclosing said material and consisting of a trough-shaped casing member that extends about the active face of the heater, and a cover which extends along the back of the heater in contact with the refractory material, the edges of the casing member being turned over said cover and meeting each other along the medial line thereof, the active face of the element having a pronounced transverse parabolic curvature so as to increase the radiating surface of said face and more widely diffuse the heat therefrom.

3. An electric strip heater comprising a resistor that extends substantially from one end of the heater to the other, a terminal at each end of the resistor, a highly compacted mass of refractory, electrical insulating, heat conducting material, enveloping said resistor and portions of the terminals, a metal casing enclosing said mass and consisting of a trough-like casing member that extends throughout the length of the heater and about

the active face thereof, a cover applied to said mass along the back of the heater and end plates set within the casing member beyond the ends of the strip and having perforations 5 through which the terminals project, the lateral edges of the casing member being turned over said cover and end plates to hold them in place, the active face of the element being transversely curved and of considerably 10 greater area than the back.

4. An electric strip heater comprising a resistor that extends substantially from one end of the heater to the other, a terminal at each end of the resistor, a highly compacted 15 mass of refractory, electrical insulating, heat conducting material enveloping said resistor and portions of the terminals, a metal sheath enclosing said mass of refractory material and consisting of a trough like casing mem- ber which extends throughout the length of 20 the heater and about the active face thereof, a cover consisting of a metal strip applied to said mass of material along the back of the heater, and end plates set within the casing member and overlapping the ends of the cover 25 and having perforations through which the aforesaid terminals project, the lateral edge portions of the casing member being turned over the cover and over said end plates to hold them in place, the said end plates and casing 30 member being pressed together beyond the mass of insulating material to provide attaching means, the active face of the element being transversely curved and of considerably 35 greater area than the back.

In testimony whereof, I hereunto affix my signature.

E. L. WIEGAND.
